(57) **CLAIM**

(21) Appl. No.: **29/306,332**

I claim the ornamental design for a travel container for powdered substances, as shown and described.

(22) Filed: **Apr. 7, 2008**

DESCRIPTION

Related U.S. Application Data

FIG. 1 is a perspective view of the travel container for powdered substances showing my new design;

(63) Continuation of application No. 29/277,089, filed on Feb. 13, 2007, now Pat. No. Des. 568,604, which is a continuation of application No. 29/251,433, filed on Jan. 5, 2006, now Pat. No. Des. 544,704.

FIG. 2 is right side perspective view thereof;

(51) LOC (9) Cl. **03-01**

FIG. 3 is a right side perspective view thereof;

(52) U.S. Cl. **D3/203.1**

FIG. 4 is a right side view thereof;

(58) **Field of Classification Search** D3/203.1,
D3/203.2, 203.3, 203.4, 203.5, 201–202,
